DESIGN

Dec. 734

Martin H. Crane, of Cincinnati, Ohio

Assignor to

Crane, Reed & Co. of Cincinnati aforesaid
Letters Patent No. 734. Dated Oct 9th 1855.

The schedule referred to in these Letters Patent and making part of the same

To all whom it may concern.

Be it known that I, Martin H. Crane,
of Cincinnati Hamilton county, Ohio, have invented a produce
a new and original shape or configuration of Metallic
Burial Cases, and I do hereby declare the following to
be a full and exact description of the same, reference being
had to the annexed drawings, making part of this
Specification and in which

Fig. 1. is a Top view of the Lid, a portion of
the screen being removed, in order to expose the illuminated
panel.

Fig. 2. is a side elevation of the case.

Fig. 3 is an end view of the case to a reduced scale.

The case proper or body is formed as follows.

The sides (a. a'. b. b') and the bottom (c), form parts of a prism, of which the bottom (c), being horizontal, the sides (b. b') are inclined outwards and slightly upward therefrom, and from these sides those (a. a') extend upward and slightly outward.

In like manner are formed the ends (A B) and (A' B'), the salient angle formed by the junction of the ends & sides, may be relieved by a flattened or fluted facet (d d'); and when so formed, the corners of the lid are scalloped or flattened (e), to match the case.

The projecting portions of the lid and body - through which the screws are passed - and called by me the whitings - are made to form collectively an ornamental cornice.

The whitings of the lid is ornamented with a beaded moulding (f), from which the central panel is raised by a cavello moulding (g).

The nearly rectangular outline of the central panel, is marked by a waving border (h), within this are the straight sides (x), and semicircular ends, (y), of the glazed opening extending nearly the full length of the panel: the margin of this opening is decorated by a beaded ornament (i) as represented.

The corners of the panel are enriched by scroll work (j), as represented. K, is the glazing in one two three or more panes, according to the size of the case or the choice of the purchaser.

The screen or cap is formed to fit & cover the glazed opening & may be secured to the lid by screws, L. M, is an emblematical composition, containing a butterfly and its just vacated shrank.

The remainder of the screen is enriched with a trellis

and foilage, &c, as represented.

I claim as new and of my invention the form and configuration of Metallic Burial Case Substantially as represented and described.

In Testimony whereof I have here set my hand before two Subscribers witness'd
